BÜROMASCHINEN-WERKE AKTIENGESELLSCHAFT, OF BENSHAUSEN, GERMANY

TYPEWRITING AND CALCULATING MACHINE

Application filed July 12, 1928, Serial No. 292,075, and in Germany July 29, 1927.

This invention relates to an appliance for the optional skipping of the comma lock in typewriting and calculating machines.

In typewriting and calculating machines it is customary to lock the writing and calculating keys in the comma position of the counting mechanisms in order to prevent the introduction of values. This locking however has been found exceedingly inconvenient when making calculations in which the commas are in some cases not written, since the operator, when working rapidly, is liable to overlook the fact that the comma place is in the operative position, and, when the calculating key locks, he only becomes aware, after a glance at the indicating device, of the fact that a calculation in this position is impossible and that the space bar must be depressed to feed the carriage forward.

This disadvantage is obviated according to the present invention owing to the fact that a member arranged on the vertical counting mechanism and controlling the locking of the calculating keys through the medium of a feeling member, at the same time controls the loose feed tooth that determines the advance of the carriage, and by means of this member the carriage can be caused to skip a plurality of steps. This controlling is only effected when actuating the numeral calculating keys, as the feeding of the carriage remains unchanged during the actuation of the numeral writing keys and also of the letter writing keys.

One constructional form of the invention is illustrated by way of example in the accompanying drawings, wherein

Fig. 1 shows a side elevation of a typewriting and calculating machine, in which certain parts of the frame are shown broken away in order to disclose other parts of the apparatus.

Fig. 2 shows a front elevation of the machine shown in Fig. 1 looking in the direction of the arrow A in Fig. 1, and

Fig. 3 shows a view of the carriage lock shown in Fig. 1, looking in the direction of the arrow B in Fig. 1.

Fig. 3a is an enlarged fragmentary view looking in the direction of the arrow B of

Figure 1, representing the mechanism in position for single step adjustment of the carriage.

Fig. 3b is a similar view, the mechanism being shown in position for two-step adjustment of the carriage.

Fig. 4 is a detail fragmentary view of the parts operated by the calculating keys, the parts being spaced for the sake of clearness.

Fig. 5 is an elevation showing a calculating key and the parts operated thereby in operative position at the moment when the coupling operating the counting slide is opened.

On a frame 1 are arranged in a known manner a front carriage rail or way rod 2 and a rear carriage rail or way rod 3, upon which the carriage 5 and the cylinder 4 are horizontally displaceable in a known manner.

On the carriage 5 is arranged a rail 6, by which vertical counting mechanisms 7 and 7' are carried in a known manner.

The carriage 5 is constantly urged from right to left, as seen in Fig. 2, by a known carriage-traction spring, not shown. When a writing key T is depressed, the traction hook T₃ is brought by a tappet lever T₂ arranged on the writing key lever T₁ into engagement with a cam shaft T₄ which revolves continuously in the direction of the arrow, whereby the traction hook T₃ is moved against the action of a spring T₅. Since the traction hook T₃ is pivoted at the point T₆ to a lever T₈, which is oscillatable about the point T₇, the lever T₈ is deflected in a clockwise direction, and by means of its pin T₉ it brings the type lever 8 into contact with the cylinder 4. Under these circumstances the lug 8a on the type lever 8 acts upon the universal bar 8b, which deflects the lever 8d, which is rotatably mounted about a point 8c, in an anti-clockwise direction. By this means a rod 8e pivoted to the lever 8d is moved in the direction of the arrow 8f, in which case it deflects against the action of the spring 8f, a carriage swing 8i, which is oscillatable about the point 8g, and 8h, and on which a loose carriage-feed tooth 82 and a fixed carriage-feed tooth 82f are arranged. If the carriage swing 8i is rocked counter-clockwise in the direction of the arrow 8f (Fig. 1) by the movement of the

85

90

95

100

rod 8e the loose feed tooth 82 is brought out of engagement with its lug 82a while the fixed feed tooth 82f is already in engagement with the ratchet-wheel 83 before the loose feed tooth 82 is disengaged. A feed of the carriage does, however, not yet take place. When the loose feed tooth 82 is brought out of engagement with the ratchet wheel 83 the spring 84 engaging therewith will act therefore 5 on and rock it about its pivot 85 to such an extent clockwise until it bears with its edge 86 against the block 81. The loose feed tooth then occupies the position shown in Figure 3a i. e. it is located with its lug 82a opposite the next tooth space 87 and it occupies this position when the type lever 8 strikes against the cylinder 4. When the type lever 8 returns to its position of rest shown in Figure 1, the swing 8i also returns to its position of rest (Fig. 1) under the action of the spring 8f₁ whereupon the fixed feed tooth 82f is brought out of engagement with the ratchet wheel 83 while the loose feed tooth 82 engages with its lug 82a in the tooth space 87 and since the ratchet wheel 83 secured on the rotatably mounted axle 83a is rotated by the carriage tension spring (not shown) over the rack 83b secured on the carriage 5 and the toothed wheel 83c secured on the axle 83a is rotated in the direction of the arrows indicated in Figures 3, 3a and 3b, the tooth 88 of the ratchet wheel 83 bears on the lug 82a of the loose feed tooth 82 and rocks it out of the position shown in Fig. 3a into the position shown in Fig. 3, whereby the carriage 5, 6 (seen in Fig. 2) is moved one step to the left.

The block 81 is provided with bosses 81a and 81b and is slidably but unrotatably mounted on the journal 81c secured in the swing 8i. The block has a pin 80 which is embraced by a bifurcated slot of the lever 78 adapted to rock about the point 79. The lever 78 has play in its connection at the point 79 so that when the swing 8i oscillates the said lever is adapted to participate in the swinging movement. There is secured on the upper end of the journal 81c a bracket 81d to which the already mentioned spring 84 is suspended. There is also connected at the point 78a of the lever 78 a lever 76 which may be moved in the direction of the arrow 76a hereinafter described.

It is obvious that in connection with the said movement or displacement of the lever 76, the block 81 will be lifted over the lever 78 out of the position shown in Fig. 3a into the position shown in Fig. 3b wherein it bears with its boss member 81a against the bracket 81d. If a type lever 8 now strikes against the cylinder 4, the loose feed tooth 82 will swing out under the tension of the spring 84 until it bears with its member 86a against the block 81, as is shown in Fig. 3b. It will swing out to such an extent that when the

type lever 8 returns to its position of rest, the said loose feed tooth 82 will not be able to drop in the next tooth space 87 of the ratchet wheel 83 but in the tooth space 89 of the ratchet wheel 83 so that it enters into engagement with the tooth 90 of the ratchet wheel 83. Consequently, it is readily obvious when comparing Figures 3a and 3b that the ratchet wheel 83 will permit the carriage 5 to move two carriage steps. On the front of the type-writing machine is fixed the calculating mechanism by its rear wall 9, which carries all the calculating mechanisms, as shown in Fig. 1. In the two side walls 1a and 1b (Fig. 2) of the frame 1 is journaled the driving shaft 10 for driving the calculating mechanism.

This driving shaft 10 is continuously rotated in the direction of the arrow 13 by a continuously rotating motor 11 through the medium of a suitable worm drive lodged in a casing 12, a ratchet wheel 14 mounted fast on the shaft 10 also participating in this rotation. Such a ratchet wheel is provided for each of the ten calculating keys 15.

The calculating-key levers 16, are rockable about a pivot 17 in the machine frame and are normally held in the position of rest, shown in Fig. 1, by a spring 20 attached at one end to a hook 18 on the lever 16 and at the other end to a stationary hook 19. The normal position of rest is determined by the hook 18 bearing against an abutment ledge 21 fixed on the machine frame. If the key 15 is depressed, and the lever 16 thereby rocked about its pivot 17 in a clockwise direction, it releases with its free arm 16a the lug 23a of a pawl 23 which is slidably arranged on a clutch disc 22, which is rotatably arranged on the shaft 10, and the pawl 23 is accordingly displaced, under the action of a compression spring 24 acting upon it, in the direction of the arrow 25, and its lug 26 comes into engagement with the continuously revolving ratchet wheel 14. By this means the disc 22 corresponding to the key that has been depressed, is coupled to the ratchet wheel 14 and therefore to the shaft 10, so that it participates in the rotation thereof. When the key 15 is depressed or the pawl 23 released by the key lever 16, a locking bar 28 slidably arranged thereon by means of a rivet 27 and of the pivot 17 is simultaneously oscillated with it, whereby its lug 29 comes out of engagement with the abutment ledge 21. As a result of this the locking bar 28, under the pull of a spring 30 attached at one end to it and at the other end to the key lever 16 slides in the direction of the arrow 31. Under these circumstances its lug 29 passes underneath the abutment ledge 21, as shown in Fig. 5, and holds the key 15 in its depressed position, while the lug 28a formed thereon moves into the path of rotation of a lug 23a formed on the pawl 23. Shortly before the completion of one complete revolution of the

clutch disc 22, which is constructed as a cam disc, the lug 23a on the pawl 23 strikes against the lug 28a, as shown in Fig. 5, on the locking bar 28, whereby the locking bar is displaced, against the action of the spring 30, in a direction opposite to that of the arrow 31. The key 16 can consequently return, under the action of the spring 20, into its normal position, shown in Fig. 1. By striking against the locking bar 28 the pawl 23 is at the same time brought out of engagement with the continuously revolving ratchet wheel 14, and thereby the cam disc 22 is stopped. When the key lever 16 returns to its position of rest, the lug 28a of the locking member 28 releases the lug 23a of the pawl 23 and immediately thereafter the lug 23a of the pawl 23 bears on the arm 16a of the key lever 16, whereby all parts again occupy their position shown in Fig. 1. The passage of the lug 23a of the pawl 23 from the lug 28a of the locking member 28 on to the arm 16a of the key lever 16 is so short that the pawl 23 cannot drop again in the ratchet wheel 14. With each cam disc 22 controlled by the calculating keys 16 is associated a value-producing member 32, which is shown broken away in Fig. 1 for the purpose of better illustration of the parts belonging to the invention, and is designated 16 in the patent application Serial No. 632,480, of April 16, 1923, now Patent 1,862,240. It is kept constantly in power-transmitting connection with the cam disc 22 by a tension spring, which is designated 18a in said patent application, attached to the member 32, by means of an anti-friction roller 33 arranged at its lower end. During the rotation of the cam disc 22 the value-producing member 32 therefore travels downwards in consequence of the construction of the curve, under the action of said spring whereby the value corresponding to the key depressed is brought into the counting mechanism 7 located in the working position, in a known manner which is described in detail in said patent application No. 632,480, and at the same time, by the action of a pin 32a, designated 34 in said application fitted to the value-producing member 32, is caused to press upon the associated key lever T₁.

It is obvious from the above that the value-producing member 32 is always pressed downward by the action of the spring not shown and will, therefore, tend to actuate the cam disc 22 in the direction of the arrow 13 in the position shown in Figs. 1 and 5. Since the spring, not shown, is considerably stronger than the spring 30 acting on the locking member 28 and the spring 30 is stronger than the spring 24 acting on the pawl 23, the effect will be attained when the lug 23a of the pawl 23 bears on the lug 28a of the locking member 28, according to Fig. 5, that the latter with its lug 29 will be

brought out of engagement with the ledge 21 and held even when the key 15 is held in the depressed position. If the key 15 is then released and the lug 23a of the pawl 23 released by the lug 28a of the locking member 28, the cam disk 22 will be further rotated in the direction of the arrow 13 by the spring (not shown) engaging on the value-producing member 32, whereby the parts again occupy the relative position shown in Fig. 1. If a key 15 is struck, only one rotation of the cam disk 22 takes place regardless of the fact whether the key 15 is immediately released again or held in the depressed position.

The apparatus hitherto described is known in all its parts and has only been briefly summarized for the better elucidation of the invention.

Underneath the calculating key levers 16, which are oscillatably supported about the pivot 17, is arranged a rocking member 34, which is supported in small bearing brackets 37 and 38 fixed to the shaft 17 and the ledge 21 and arranged to left and right in the machine frame, by means of journals 35 and 36 formed on the said rocking member, as shown in Figs. 1, 2, and 4 and is held in the position illustrated in Fig. 1, by a spring not shown. On the left-hand side of the rocking member 34 is formed a pin 39, to which is attached a connecting rod 40, which is pivotally connected at its other end by a pin 41 with a lever 42, which is oscillatable about the pivot 17.

To the free arm of the lever 42 is fitted a roller 43, by means of which it can act upon a rod 44. The rod 44 is provided at its lower part with a longitudinal slot 45, in which a screw extension 46 engages and thereby guides the rod 44. At its upper end the rod 44 is guided by virtue of the fact that by means of a lug or flap 48 formed thereon projecting through a slot 47 into the calculating mechanism it is pivotally connected by a screw 51 with a lever 50 which is rotatable about a bolt 49 on the machine frame. The lever 50 is normally held by the weight of the rod 44 in the position shown in Fig. 2.

To the machine frame is pivoted by means of a screw 52 a lever 53 which is normally pulled by a spring 54 against an abutment 55. This lever 53, with a lug 56 formed thereon, feels bars 7a arranged on the vertical counting mechanisms 7. These bars have recesses 7b at the comma positions of the counting mechanism, and the lug 56 on the lever 53 can engage in these recesses. Moreover in the bar 7a, recesses 7c are provided, which correspond to the right and left side walls of the counting mechanism. The position which the lever 53 occupies when engaging in a recess, is shown in Fig. 2.

If a calculating key 15 is depressed, the key lever 16 deflects about the pivot 17 in a clockwise direction. Owing to this the lug

18 formed thereon strikes against the rocking member 34 and rocks the latter in a clockwise direction. This rocking movement is transmitted by the connecting rod 40 to the lever 42 so that the same is deflected in a clockwise direction. During this deflection the roller 43 arranged on the lever 42 acts upon the rod 44 and raises it. The rod 44 thereby rocks the lever 50 about its pivot 49 in a clockwise direction. This rocking movement can however only take place when the lever 53 is not projecting into the path of oscillation of the lever 50, that is, when the lever 50 is rocked by the action of the bar 7a of the vertical counting mechanism 7 in a clockwise direction in such a way that it comes out of the operative position in relation to the lever 50. This however is only the case when a counting position of the corresponding vertical counting mechanism is in the operative condition. In the other case the lever 53 lies in the path of oscillation of the lever 50, as illustrated in Fig. 2, whereby a deflection of the lever 50 and therefore a raising of the rod 44 is prevented. In this way an oscillation of the lever 42 and of the rocking member 34 and therefore a depression of a calculating key 15 is prevented.

The position illustrated in Fig. 2 shows the left-hand side wall of the vertical counting mechanism in the working position of the machine. Now if the next counting position of the vertical counting mechanism is to come into the operative condition, the carriage is moved one step to the left by striking the known space bar L, in which case the projecting part 7d formed on the bar 7a runs on to the lug 56 of the lever 53 and thereby oscillates the latter against the action of the tension spring 54, so that now the lever 53 sets free the lever 50.

Hence a depression of the calculating keys 15 can only take place when a counting position stands in the working position but not when a side wall stands in the working position. If a comma position comes into the operative position, the lug 56 of the lever 53 enters one of the recesses 7b and likewise locks the calculating keys. The same thing also happens if the right-hand side wall enters the working position of the machine.

Upon a comma position of the counting mechanism entering the working position of the machine, the calculating keys 15, in the constructional form described above, are therefore locked against depression. In order to pass from the comma position into the next calculating position of the counting mechanism, it is necessary, as known, to strike the comma key, or, if the writing of the comma is not desired, to strike the space bar. The latter method of working is however a waste of time, inasmuch as the operator must first pay attention to the locking of the cal-

culating keys in order then to depress the space bar.

In order to obviate this loss of time a device is provided by means of which the machine can be so adjusted that the paper carriage or the counting mechanism does not first remain in the comma position at all but skips it at once. This is effected by means of a device hereinafter described, which is controlled from the vertical counting mechanism, and which influences the loose carriage feed tooth cooperating with the ratchet wheel in such a way that after the striking of a calculating key in the counting mechanism position located at the left-hand side of the comma a double-carriage step is effected.

In order to attain this, there are arranged on the bar 7a, which serves for controlling the locking lever 53, forwardly projecting lugs 7x and 7x₁, which are located in the vertical plane of the counting mechanism positions located on the left beside the existing comma positions. With these lugs there cooperates a feeling lever 57, which is pivoted to the machine frame by means of the same screw 52 as the lever 53, and is constantly urged in an anti-clockwise direction by a spring 58, so that in its position of rest it bears against a stationary abutment pin 59.

In the front wall of the calculating mechanism is rotatably supported an adjusting knob 61, which is provided with a pointer 60 and at the rear end of which is fixedly arranged a lever 62, which has a rearwardly projecting flap or lug 63. This flap 63 is provided with a bore, in which a rod 64 is so supported as to be slidable in an axial direction and is held by a spring 65 constantly in a definite position in relation to the lever 62 and its flap 63. A pin 66 arranged in the rod 64 bears from the rear against the flap 63, against which there bears on the other side the spring 65, which at the other end constantly urges a disc 68, which is secured to the rod 64 by means of a pin 67, in the direction of the arrow 69. The rod 64 is slidably supported at its left-hand end in a hole 70, shown in Fig. 2, in a bell-crank lever 72, which is oscillatably arranged on the machine frame by means of a screw extension 71.

The bell-crank lever 72 is connected by means of the rod 73, with the bell-crank lever 75, which is oscillatably arranged on the rear part of the machine by means of the bolt 74, a rod 76 being pivoted by means of a bolt 77 to a rearwardly projecting arm of the bell-crank lever 75. The rod 76 is pivotally connected at the point 78a, as shown in Figs. 3a and 3b, with a lever 78, which is rotatably supported on the machine frame at its right-hand end at the point 79, and with its free fork-shaped end embraces a pin 80 on a raising block 81.

The method of operation is as follows:— If for example the hundreds-of-thousands

position of the counting mechanism 7 stands in the working position of the machine and a calculating key corresponding to the value "6" is struck, the corresponding amount is reckoned in the counting mechanism and the carriage carrying the counting mechanisms springs one step to the left, so that the tens-of-thousands position of the counting mechanism moves into the working position 10 of the machine. If a calculating key is again struck, for instance the key corresponding to the value "2", and the carriage feed takes place accordingly, the thousands position of the counting mechanism moves into the operative position. Under these circumstances the lug 7x at the same time runs up on to the feeling lever 57 and rocks it against the action of the tension spring 58 attached to it, in which case the said feeling lever 57 20 acts upon the rod 64 with the downwardly projecting flap or lug 57a formed on it. By this means the rod 64 is shifted to the left and thereby moves out of the hole 70 in the lever 72 into the path of movement of the extension 44a of the rod 44. If a calculating key is now struck again, for instance the one corresponding to the number "5", the amount is reckoned in the known manner. During this procedure the upwardly traveling rod 44 30 strikes with the shoulder 44a formed thereon against the rod 64 projecting into its path, and moves the latter upwards, whereby a rocking of the bell-crank lever 72 is brought about in an anti-clockwise direction. This results, by means of the connecting rod 73, in a rocking of the bell-crank lever 75 about the pivot 74, whereby the rod 76 in its turn is raised, and through the medium of the lever 78 effects the raising of the raising block 81 into the position shown in Fig. 3b. 40

Owing to this the loose feed tooth deflects until its edge 86a bears against the raising block 81, as shown in Fig. 3b, this oscillation corresponding in amplitude to two teeth of the ratchet wheel, so that upon the shoulder 8a of the type lever 8 striking against the universal bar 8b a springing of the carriage is effected not merely through one carriage step but through two carriage steps. Hence the carriage or the counting mechanism springs directly from the thousands position into the hundreds position, skipping the position of the comma. The lever 57 is then released again by the cam 7x, so that under the influence of its spring 58 it returns to the position shown in Fig. 2. By this process the flap 57a also sets free the rod 64, so that it is pulled by its spring 65 out of reach of the shoulder 44a of the rod 44, whereby also the raising block 81 falls under the influence of the intrinsic weight of its rod gear into the normal position shown in Figs. 3 and 3a.

If in the further course of the calculation the counting mechanism then passes from the tens into the units position, the lever 57

is similarly deflected, as described above, by the pin 7x, and the rod 64 is displaced towards the left into the path of the shoulder 44a of the rod 44, so that then, upon the calculating key being struck in the units position, the raising block 81 is raised in the manner described above and a double carriage step is again thereby brought about. Hence the counting mechanism together with the carriage, springs directly from the units position into the first decimal place, skipping the decimal point. 70 75

By providing a correspondingly deeper lug 7x on the counting mechanism and a second, higher shoulder 44b on the rod 44 the raising block 81 can be raised so high that the feed tooth 82 can swing right out, so that a three-fold step of the carriage is brought about and a jumping is possible from the lowest position of one counting mechanism 7 into the highest position of the next counting mechanism 7.

As has already been mentioned above, the adjusting knob 61 is rotatably supported in the front wall of the calculating mechanism. Normally it occupies the position illustrated in Fig. 2, in which the pointer 60 fitted to it points to the indication "with period skipping". If however the knob is rotated in such a way that its pointer points to the words "without period skipping", the lever 62, which is rigidly connected with it, is at the same time oscillated, whereby the rod 64 is brought out of the path of the lever 57. The possibility is thereby given of suspending at will the automatic skipping of the comma positions when striking the numeral keys 15, that is, when writing and calculating. 95 100

It should be particularly emphasized that the device for skipping the comma positions, in consequence of the movement for raising the raising block being obtained from the rod 44, is only operative when striking the calculating keys 15, while when striking the normal writing keys T by hand it is completely inoperative, as in this case no movement of the rod 44 occurs. The counting mechanism or the lugs formed thereon can act upon the lever 57 during the running of the carriage in the usual manner without the raising block being affected in any way, irrespectively of whether the knob is adjusted to "with period" skipping or to "without period" skipping. Thus if the operator 110 115 passes from the numeral keys 15 to the writing keys T, nothing special need be done to render inoperative the double-step or comma-skipping device, but this device remains inoperative, for the reasons hereinbefore set forth, when the writing keys are struck. 120 125

What I claim is:—

1. A typewriting and calculating machine including numeral calculating keys, numeral writing keys and a counting mechanism having a controlling member wherein when oper- 130

ating the numeral calculating keys at the comma position a skipping of the carriage is automatically released by the cooperation of the controlling member on the counting mechanism characterized by the fact that when using numeral writing keys the controlling member remains inoperative on the means effecting the skipping of the carriage.

2. A typewriting and calculating machine including numeral calculating keys, numeral writing keys, a carriage, space skipping mechanism including a loose tooth and controlling means therefor and counting mechanism, a controlling member associated with the counting mechanism, and a coupling member establishing connection between the numeral calculating keys and the loose tooth controlling means upon operation of the controlling member.
3. A machine as claimed in claim 2 in which the coupling member is adjusted by mechanism actuated by the numeral calculating keys, which mechanism also forms a part of a locking mechanism for the calculating machine, said locking mechanism being rendered effective during space skipping operation of the carriage.

4. In a typewriting and calculating machine, a movable carriage, a carriage controlling member, a key operated member, a carriage operated slideable connecting rod between said two members, and carrying means for said rod manually operable for rendering said connections between said two members inoperative.

In testimony whereof I have signed my name to this specification.

GUSTAV MEZ.
